UNITED STATES PATENT OFFICE

160,436

CHINA MARKING PENCIL

Ernest H. Seibert, Chicago, Ill., assignor to Auto-point Company, Chicago, Ill., a corporation of Illinois

Application February 15, 1950, Serial No. 7,936

Term of patent 14 years

(Cl. D74—24)

To all whom it may concern:

Be it known that I, Ernest H. Seibert, a citizen of the United States, residing at Chicago, in the county of Cook and State of Illinois, have invented a new, original, and ornamental Design for a China Marking Pencil, of which the following is a specification, reference being had to the accompanying drawing forming a part thereof.

In the drawing:

Figure 1 is a front elevational view showing my new design of a china marking pencil;

Fig. 2 is a side elevational view thereof;

Fig. 3 is a top plan view thereof; and

Fig. 4 is a bottom plan view thereof.

I claim:

The ornamental design for a china marking pencil, substantially as shown,

ERNEST H. SEIBERT.
